UNITED STATES PATENT OFFICE.

M. H. BUCKNALL, OF DARIEN, WISCONSIN.

IMPROVEMENT IN CULTIVATORS.

Specification forming part of Letters Patent No. 57,856, dated September 11, 1866.

To all whom it may concern:

Be it known that I, M. H. BUCKNALL, of Darien, Walworth county, State of Wisconsin, have invented a new and Improved Cultivator; and I do hereby declare that the following is a full, clear, and exact description thereof, which will enable others skilled in the art to make and use the same, reference being had to the accompanying drawings, forming part of this specification, in which—

Figure 1 is a side sectional view of my invention, taken in the line x x , Fig. 2; Fig. 2, a plan or top view of the same; Fig. 3, a vertical section of a portion of the same, taken on the line y y , Fig. 2; Fig. 4, a detached front view of one of the teeth of the cultivator.

Similar letters of reference indicate like parts.

This invention relates to a new and improved cultivator for cultivating plowed ground, eradicating the weeds therefrom, and pulverizing the soil.

The invention consists in a novel construction of the device, whereby the teeth may be made to penetrate into the earth at a greater or less depth, as may be desired, and elevated entirely above the surface of the ground when occasion may require—as, for instance, in drawing the device from place to place.

The invention also consists in a novel manner of attaching the draft-pole to the machine, and in a novel construction or arrangement of the cultivator-teeth, as hereinafter fully set forth.

A represents a rectangular frame, to the front end of which two lever-frames, B B, are attached by joints a a . These lever-frames have curved or segment guides C C passing through them, the lower ends of said guides being attached by joints b to the frame A, and having a series of holes, c , made in them, through any of which pins d in the lever-frames pass, said pins having spiral springs e on them to force the pins into the holes as the lever-frames are raised or lowered.

The frame A is supported by two wheels, D D, the axles E of which are secured to the

lever-frames B B, and it will be seen that by adjusting the lever-frames higher or lower the frame A may be raised or lowered at a greater or less depth above the surface of the ground.

F represents the draft-pole of the machine, the rear end of which is secured by a bolt, f , to one of the cross-bars g of the frame A, and is secured to the front cross-bar, h , of said frame by means of a yoke, G, having two screw-bolts, i i , passing through its ends, one at each side of the draft-pole, F, a wooden block, j , being at the bottom of the yoke, on which the draft-pole rests.

These blocks j may be changed, those of greater or less thickness used, in order to give the draft-pole a greater or less degree of elevation, as may be required.

The double-tree H is attached to the draft-pole as usual.

I represents the standards, to which the teeth J are attached. These standards are of cylindrical form, and pass through the framing, the latter resting on shoulders k on the standards, and the upper ends of the latter having screw-nuts l upon them. (See Fig. 1.) These standards are braced by inclined rods m .

The lower parts of teeth J are of diamond or lozenge shape, gradually tapering at their upper parts and bent in semi-cylindrical form, so as to fit over the standards I, the upper ends of the teeth having lips n , which are bent around the standards, so as to completely encompass them.

The standards I are curved forward at their lower parts, and the teeth J are also curved in a similar direction.

By this arrangement the cultivator-teeth are firmly secured in position, being well braced, and the lower ends of the teeth are secured by rivets o to the lower ends of the standards.

The teeth, it will be seen, may be made to penetrate the earth at a greater or less distance by adjusting the frame A higher or lower, and the teeth may be elevated entirely above the ground when necessary—as, for in-

stance, in drawing the device from place to place.

Having thus described my invention, I claim as new and desire to secure by Letters Patent—

1. The lever-frames B B, attached at their front ends by joints *a a* to the front end of the frame A, in combination with the segment-guides C C and the stop-pins *d*, or their equivalents, substantially as and for the purpose herein set forth.

2. The combination of the teeth J, standards I, rivets *o*, shoulders *k*, screw-nut *l*, braces *m*, and frame A, substantially as described, for the purpose specified.

M. H. BUCKNALL.
